SPARK PLUG HAVING A SECTIONAL CENTER ELECTRODE AND A THIN METALLIC SLEEVE SURROUNDING THE LOWER PORTION THEREOF

George Forbes Taylor, Vancouver, British Columbia, Canada, assignor to Fay Dyn Products Ltd., Vancouver, British Columbia, Canada, a corporation of British Columbia

Continuation of application Ser. No. 165,625, Jan. 11, 1962, which is a continuation of application Ser. No. 566,386, July 19, 1966. This application May 22, 1967, Ser. No. 640,426

1 Claim. (Cl. 313—136)

The present invention relates to spark plugs and in particular to apertured spark plugs designed for use under high pressure conditions such as those encountered in jet engines and high compression automotive engines.

This application is a continuation of my previous application, Ser. No. 566,386, filed July 19, 1966, now abandoned, which is a continuation of my previous application, Ser. No. 165,625, filed Jan. 11, 1962, now abandoned.

The invention consists in the particular arrangement and combination of parts hereinafter to be described and to be pointed out in the appended claims.

In the description that follows reference will be had to the accompanying drawings in which:

FIGURE 1 is a sectional elevation of a spark plug constructed according to the invention;

FIGURE 2 is an elevation partly in section of another embodiment of the invention;

FIGURE 3 is an elevation partly in section of a further embodiment of the invention; and

FIGURE 4 is a sectional elevation of the electrode assembly of FIGURE 3 on an enlarged scale.

In the drawings the spark plug 1 comprises the conventional metal jacket 2 carrying the usual grounded electrode 3. Hollow ceramic porcelain body 4 is mounted within metal jacket 1 on shoulders 5 which may be squared as in FIGURE 1 or sloped or rounded as in FIGURES 2 and 3. Suitable sealing gaskets 6 and 7 prevent the escape of gases between the wall of the porcelain body 4 and the metal jacket 2.

The plugs shown in FIGURES 1, 2 and 3 are threaded at 8, 8A, and 9 respectively to the corresponding threaded section on the cylinder head (not shown).

In the embodiments shown in FIGURES 1 and 2, metal connector cap 10 is centrally apertured or channelled at 11 over its entire length. A screw threaded connection 12 is provided between the connectors 10 and the porcelain bodies 4. A shoulder 13 on the cap 10 abuts the upper end of porcelain body 4, a sealing gasket 14 being provided between the cap 10 and the porcelain body.

FIGURE 1 shows a carbon pole 15 mounted within a metal cylinder 15A positioned in hollow porcelain body 4, on shoulder 16. An apertured or channelled electrode member or tip such as tube 17 is mounted in the lower portion of the porcelain body and terminates beyond the end of the porcelain at a point adjacent to but not touching grounded electrode 3. It will be noted that carbon pole 15 is penetrated at its lower end by tube 17 and at its upper end by a tubular metallic extension 18 on cap 10. In addition the plug of FIGURE 1 has been provided with a thin metallic electrode sleeve 17A between porcelain bodies 4 and the apertured or channelled electrode 17.

The embodiment of the invention shown in FIGURE 2 is in structure substantially the same as that of FIGURE 1. However in FIGURE 2 the carbon pole 15 of

2

FIGURE 1 has been replaced by a tightly-packed plug 19 made of metallic wool and tube 17 has been replaced by rod 17B having an outwardly extending tip 20. The plug 19 is in electrical contact with channelled rod 17B and cap member 10.

In FIGURES 3 and 4 metal connector cap 100 is secured to porcelain body 101 by means of a screw threaded connection 103, a sealing gasket 104 being positioned between shoulder 104 on cap 100 and the upper end of porcelain body 101. The carbon pole of the structure shown in FIGURE 1 has been replaced in FIGURE 3 by a channelled member such as metal tube 105. Aper-tured or channelled electrode tip 106 is welded endwise of and within aperture 107 in tube 105 thereby sealing the lower end of the aperture. The apertures in electrode tip 106 are shown in the form of slots or channels 108 extending lengthwise of the electrode in the outer surface thereof.

Aperture 109 in cap 100 is in alignment with aperture 107 in tube 105, the one aperture extending into the other, the two apertures being loaded with a conglomerate 110 formed of conducting materials such as carbon granules, metallic wool and metal granules either layered or in admixture.

25 The spark plugs of the present invention which have apertured connecting caps and tubular electrode tips with porous electrode poles therebetween retain their conductive properties for extremely long periods of time and are in addition capable of withstanding extremely high cylinder pressures.

I claim:

1. A spark plug having a hollow electrically insulating body, a sectional electrode formed in said body including at least an upper electrode section, a central electrode section and a lower electrode section, said upper section being a connecting cap and having means for carrying current therethrough to the central section and being in electrical connection with said central section, the central section being positioned within said insulating body and packed with a porous electrically conducting material and said lower electrode section having an inner end located within said insulating body and an outer end positioned near a ground electrode of the plug, said lower electrode section comprising a rod of electrically conducting material and a thin metallic sleeve of electrically conducting material surrounding the rod and adjacent thereto from said inner end to said outer end, the inner ends of both the rod and the sleeve being in electrical contact with the said porous electrically conducting material of the central section, said lower electrode section having a plurality of relatively small channels formed therein and extending longitudinally thereof from said inner end to said outer end.
